TRIGGER MECHANISM

Reginald Vernon Shepherd and Harold John Turpin, London, England

Application September 9, 1942, Serial No. 457,792
In Great Britain April 17, 1941

2 Claims. (Cl. 42—3)

This invention relates to machine guns or rifles, and has, as its main object, to simplify the construction thereof, so as to facilitate manufacture by mass production methods. Whilst not limited thereto, the invention is particularly applicable to machine carbines, i. e., short-barrel machine guns.

One object of the invention is to provide an improved trigger mechanism which is simple in action, has relatively few moving parts, and can readily and cheaply be produced by mass production methods. Such an improved trigger mechanism may comprise an actuating lever for transmitting movement of the trigger to the sear, this lever also acting as a member for selecting either automatic or single shot firing of the gun when the trigger is operated. Preferably the actuating lever constitutes the sole operating member between the trigger and the sear.

The invention may be carried into practice in various ways, and one convenient construction of machine carbine in accordance therewith will now be described by way of example with reference to the accompanying drawing in which—

Fig. 1 is a longitudinal sectional view of a construction embodying the invention, the bolt being shown in an intermediate position between the cocked position and the firing position;

Fig. 2 is a transverse section taken on the line 2—2 of Fig. 1, certain parts being removed; and Fig. 3 is a transverse section taken on the line 3—3 of Fig. 1, with the mechanism adjusted for automatic firing.

The construction of carbine shown in these figures comprises a tubular metal casing A extending rearwardly from the breech end of the barrel which contains the bolt D which is of substantially cylindrical form and fits within the casing so that it can reciprocate freely. The bolt is relatively heavy, and thus has a large inertia as compared with that of the bullet. Moreover it is normally forced toward the breech by a compression spring D¹—hereinafter referred to as the return spring—disposed between the rear end of the bolt D and the end of the casing. The bolt is not locked during firing and is thus moved rearwardly by the backward thrust of the cartridge following firing, the inertia of the bolt and the strength of the return spring D¹ ensuring sufficient time delay for the bullet to leave the barrel before there is an appreciable opening between the bolt and the barrel.

The rear end of the bolt has a shank D⁸ of reduced diameter for insertion into the front end of the helical return spring D¹. In the neighbour-

hood of the shoulder thus formed, there is a transverse hole to receive the shank of a cocking handle D⁹ which projects through a slot in the casing A.

5 The rear end of the casing A is open and the rear abutment of the spring D¹ is constituted by a removable cup A² which fits within and closes the end of the casing. The cup A² is held in position by a front end plate C¹ on the removable butt part of which is shown at C and at the same time acts as a retaining catch for the butt. The cup A² has a rearwardly projecting boss or spigot A³ which engages in a hole in the butt plate C¹ so as to prevent further rotational movement of the plate when it has been positioned on the end of the casing. The butt plate C¹ also has a pin C³ to engage in a slot H¹ in the rear wall H of a trigger mechanism casing attached to the underside of the casing A, the arrangement being such that the pin C³ enters the slot H¹ when the plate C¹ is inclined (in a plane perpendicular to the barrel axis) to its normal position. Rotation of the butt to bring the hole in the butt plate C¹ into alignment with the boss A³ locks the pin and slot 10 connection and at the same time brings the upper edge of the plate C¹ under an overhung flange A⁴ fixed to or forming part of the main casing. The pin and slot connection C³—H¹ in conjunction with the overhung flange A⁴ thus prevent rearward movement of the plate C¹, and therefore of the abutment cup A² of the return spring, whilst the boss A³ on the cup prevents unlocking rotational movement of the butt plate. To release the butt, it is only necessary to press the outer 15 surface of the boss A³ of the cup, which is accessible through the hole in the plate C¹, and at the same time to rotate the butt.

In order to prevent any tendency which the return spring may have to buckle or to rub 20 against the walls of the casing, the cup A² has a forwardly projecting cylindrical skirt A⁶ with a flared forward end. If desired the skirt and the cap may be formed separately, the skirt being in the form of a cylinder with its rear end extending into the cup, fullered and fastened to the inside wall of the cup, for example by spot welding or by riveting.

25 Preferably, as shown in Figure 1, the rear surface of the cup A² abuts against a removable cap A⁷ which closes the end of the main casing and is held in position by the front end plate of the removable butt. The cap A⁷ has a central hole through which the boss A³ projects to engage in the hole in the butt plate C¹. The cap A⁷ retains the cup A² and associated sleeve A⁶ in the end of

the casing when the butt plate C¹ is removed by pressing the spigot A³ and rotating the butt C as described above.

The trigger mechanism casing is mounted on the underside and at the rear end of the main casing and consists of a pair of parallel vertical side walls H²H³, having their upper edges welded or otherwise fixed to the main casing, and the rear wall H containing, as has already been described, the slot H¹ for the fixing pin on the butt plate. The mechanism itself comprises a trigger J pivoted at J¹ between the side walls near the rear edge thereof, a sear K pivoted at K¹ between the walls near the front edge thereof, and an actuating lever L pivoted at J² on the trigger J and extending forwardly therefrom so as to constitute the sole operating member between the trigger J and the sear K and also to act, in a manner to be described, as a member for selecting single shot or automatic firing of the carbine when the trigger is pressed. In addition the mechanism includes a member L¹ for controlling the selection by the actuating lever L, a tension spring L² extending between the trigger J and the sear K, and a bell crank lever K² pivoted on the sear for transmitting force exerted by the spring to the actuating lever.

The trigger J comprises a stamping bent so as to have a cross-section of substantially channel form in order to give it rigidity, the sides of the channel tapering from a maximum width near the upper part of the trigger the pivot J¹ at which comprises a horizontal pin supported in holes in the side walls of the mechanism casing, to a minimum width at the lower operating part of the trigger. At the upper end of the trigger the web is cut away at J³ to provide a clearance space for the lever L the pivot J² for which is fixed in the sides of the channel. A part J⁴ of the web below the pivot J¹ is stamped out to form a hook for the tension spring L² which extends forwardly and thus tends to move the trigger in a clockwise direction about its pivot, that is, towards the "off" position. The rear edges of the sides of the channel, at their widest parts, are slotted as indicated at J⁵ and the sides of the slots co-operate with a fixed transverse pin J⁶ extending between the sides H²H³, to act as stops for limiting pivotal movement of the trigger J in each direction. Ears J⁷ are also stamped out of the sides of the channel and are bent outwardly so as to engage the inner surfaces of the walls H²H³ and thus to centre the trigger between the walls.

The trigger guard J⁸ consists of a metal strip having a width equal to the distance between the inner surfaces of the walls H²H³ and bent into substantially U-shape. The ends of the strip are inserted between the walls and are welded or otherwise fixed in position so that they also act as distance pieces for maintaining the lower edges of the side walls the correct distance apart. The trigger guard is positioned so that the rear limb is close to the back plate H and the strip thus protects and in part closes the lower edge of the trigger casing. The end of the trigger casing in front of the front limb of the guard is closed by means of a hand grip of wood M, or of a moulded material such as the material sold under the registered trade-mark "Bakelite," which covers the forward part of the trigger casing and part of the lower surface of the main casing A, this grip being held in place by screw threaded studs. The hand grip M when in position, also prevents withdrawal of the pivot pins J¹ and K¹ for the trigger

J and the sear K, the pin J¹, since its ends are not normally covered by the hand grip M, being arranged to project from one side wall of the casing and being bent over, as indicated by the broken line J⁹ in Figure 1, so as to extend substantially along the outside of the wall H³ to a point beneath the hand grip M. Preferably the end of the extension of the pin is turned inwardly so as to engage in a hole or recess J¹⁰ in the side wall H³.

The sear K consists of a two-armed bell crank lever pivoted between the side walls so that the upper arm K³ extends rearwardly and substantially horizontally, whilst the lower arm K⁴ extends downwardly. Rotation of the sear in a counter-clockwise direction thus tends to move a nose K⁵ on the upper surface of the horizontal arm through an aperture in the underside of the main casing A into the path of a lug D¹¹ on the underside of the bolt. The lower end of the arm K⁴ is of reduced width so as to form a "step" K⁶ about half way between the pivot K¹ and the end of the arm. This step constitutes a projection or lug which normally engages in a notch L³ in the lever L so that the longitudinal forward movement of lever L as the trigger J is depressed causes clockwise rotation of the sear K about its pivot to lower the nose K⁵ and thus release the bolt D.

The lever L extends forwardly beyond the notch L³ and is bent upwardly to form a nose L⁴ so that normally the end thereof lies in the path of the lug D¹¹ on the bolt, the end being rounded so that it does not act as a catch to prevent reciprocating movement of the bolt. The lug D¹¹ does, however, when it engages the nose L⁴, cause downward movement thereof, that is, rotation of the lever L in a counter-clockwise direction about its pivot J², the downward movement being sufficient to free the step K⁶ from the notch L³. The sear thus returns to its operative position automatically and even though the trigger may still be depressed, engages the lug D¹¹ as the bolt is moved forwardly by the return spring D¹ after the recoil following firing. As thus far described the trigger mechanism is set for single shot firing of the gun.

The arm K⁴ of the sear carries near its end a horizontal pivot pin for the bell crank lever, K², which may comprise a stiff spring steel wire coiled to form the lever pivot bearing, with one arm K⁷ bent to engage the under surface of the lever L whilst the other arm K⁸ is bent to form an attachment hook for the forward end of the tension spring L². This spring thus serves three purposes, namely as a return spring for both the trigger J and the sear K and also as a return spring for the actuating lever L since, due to the upward pressure exerted on the underside of the lever by the arm K⁷, the upper surface is maintained in contact with the "step" K⁶ on the sear and the lever is moved upwardly following depression thereof by the lug D¹¹.

In order that the lever L may also act as a selecting member for automatic and single shot firing, the lug D¹¹ is, as shown most clearly in Figures 2 and 3, unsymmetrically arranged so that by transverse movement of the forward end of the actuating lever, the nose L⁴ can be brought into a position in which it is not engaged by the lug D¹¹ during reciprocation of the bolt. Since with the lever in this position the connection between the lever L and the sear K is not tripped, the bolt is free to move backwards and forwards as long as the trigger J is held depressed, and the gun fires automatically.

Selecting movement of the lever L is effected by a transverse pin L¹ (Figure 2) which is supported by the walls H² and H³, so that it can slide longitudinally between two limiting positions respectively determined by a collar L⁵ formed on the pin and by a split ring L⁶ in an annular groove, the collar and the ring being on opposite sides of the wall H². The pin L¹ has an annular groove L⁷ which constitutes a guide channel for the lever L so that longitudinal movement of the pin causes transverse movement of the lever between two positions in which the nose L⁴ is respectively in the path and out of the path of the lug D¹¹. The pin is held in each of its two positions by ball catches L⁸ arranged so that the balls engage the edges of the side wall H³.

It is to be understood that the specific constructions described above are by way of example only and that the form of the individual components may be varied as necessary within the scope of the invention as defined in the appended claims.

We claim as our invention:

1. In an automatic firearm having a bolt which reciprocates automatically on firing, a trigger mechanism comprising a trigger, a pivoted sear having one arm for holding the bolt in the cocked position and a projection on the other arm, an actuating lever, a notch in said lever arranged to engage said projection, said lever being pivoted at its rear end on the trigger so that operation of the trigger causes said lever to move forwardly to rotate the sear through the medium of said projection and notch and release the bolt, a bell-crank lever mounted on said other arm of the sear, one arm of the bell crank lever being arranged to engage said actuating lever, a spring connected between the other arm of the bell-crank lever and the trigger so

that the first-mentioned arm of the bell-crank lever exerts pressure on said actuating lever to force said notch into contact with said projection, a lug on the bolt, and selecting means which can be operated to move said actuating lever into a position where it is struck by said lug to disengage said notch and projection against the action of said bell-crank lever and thus release the sear.

- 10 2. In an automatic firearm having a bolt which reciprocates automatically on firing, a trigger mechanism comprising a casing, a trigger, a pivoted sear having one arm for holding the bolt in the cocked position and a projection on the other arm, an actuating lever, a notch in said lever arranged to engage said projection, said lever being pivoted at its rear end on the trigger so that operation of the trigger causes said lever to move forwardly to rotate the sear through the medium of said projection and notch and release the bolt, an upturned forward end on said lever, a bell-crank lever mounted on said other arm of the sear, one arm of the bell crank lever being arranged to engage said actuating lever, a spring connected between the other arm of the bell-crank lever and the trigger so that the first-mentioned arm of the bell-crank lever exerts upward pressure on said actuating lever to force said notch into engagement with
- 15 30 35 said projection, a lug on the bolt, and a transverse selector pin slidably mounted in said casing and engaging said actuating lever, which pin can be moved to shift said actuating lever transversely into a position in which said upturned forward end is struck by said lug to disengage said notch and projection against the action of the bell-crank lever and thus release the sear.

REGINALD VERNON SHEPHERD.
HAROLD JOHN TURPIN.
